MANGLE

Elmer Paul Harrison and Orville A. Hunt, Oklahoma City, Okla.; said Hunt assignor to said Harrison

Application January 26, 1940, Serial No. 315,791

14 Claims. (Cl. 38—57)

This invention relates to mangles or ironing machines and more particularly to the type used in commercial laundering establishments.

Mangles of usual construction include a steam heated ironing shoe in the form of a steam chest, and a power rotated co-operating ironing roller having a padded cloth surface. As wet clothing passes thru such a mangle, moisture is removed in the form of steam, and the speed at which the mangle can be operated, and consequently the speed at which wet clothing can be ironed, depends almost entirely on the temperature which can be maintained on the cloth contacting surface of the shoe, and on the contacting surface of the roller during its actual contact with the cloth. Naturally, the wet clothing tends to cool these surfaces. Since the padded surface of the roller is not independently heated, but depends on its proximity to the heated ironing shoe for its heat, this surface can rarely be maintained at a temperature as high as 212° F. during the ironing operation. For this reason the padded surface of the roller gradually picks up more and more moisture from the wet clothing, and its temperature tends to drop lower. This further lowers the speed at which clothing can be ironed.

In view of these difficulties, it is the chief object of this invention to provide a mangle in which the padded ironing surface of the ironing roller is supplementally heated independently from the ironing shoe, and can, therefore, be maintained at a temperature sufficiently high, during the ironing operation, to prevent it from absorbing moisture, and also to render it capable of aiding the ironing shoe in completely removing the moisture from the cloth being ironed. Such a device, naturally, is capable of ironing clothing, flat work, etc., at a much higher rate of speed than most mangles presently in commercial use, and such an increase in ironing speed naturally means reduced laundry operating costs.

The details in the construction of several preferred embodiments of the invention, together with other objects attending its production, will be better understood from the following description when it is read in connection with the accompanying drawings, which are chosen for illustrative purposes only, and in which,

Figure 1 is a perspective view of a unitary portion of a machine embodying the invention;

Figure 2 is an end view of that portion of the machine illustrated in Figure 1, with parts cut away to show constructional details and includes a wiring diagram;

Figure 3 is a top plan view of that portion of the machine illustrated in Figure 1;

Figure 4 is a side view of a portion of a machine which embodies a plurality of the units illustrated in Figure 1;

Figure 5 is a top plan view of a unitary portion of a machine which includes a slightly different embodiment of the invention than is illustrated in Figures 1 to 3 inclusive;

Figure 6 is an end view, with parts cut away and parts in section, of the portion of the device illustrated in Figure 5; and

Figure 7 is a view similar to Figure 6, and illustrates a slightly different embodiment of the invention than is illustrated in the other views.

The embodiment of the invention illustrated in detail in Figures 1 to 3 inclusive a steam chest 10, the surface of which may be shaped to form one or more arcuate ironing shoes 11, each of which is adapted to co-operate with an ironing roller 12. As illustrated in Figure 4, a complete mangle may include a battery of four to eight ironing rollers 12, arranged in parallel relation, and co-operating shoes 11 formed in the steam chest 10. The shafts 13 on which these rollers are mounted are preferably journaled in adjustably mounted side plates 14 and 15. These plates may be moved vertically toward or away from the chest 10 so that all the rollers 12 are simultaneously moved toward or away from their respective shoes. In addition the bearing blocks 16 and 17, which journal the opposite ends of the shafts 13, are adjustably mounted in the respective plates 14 and 15, and are responsive to adjusting screws 18 and 19 respectively to move the individual rollers 12 toward or away from their respective ironing shoes.

As is well known to those familiar with the art, the peripheral surface of the ironing rollers 12 is usually padded with cloth or other suitable padding, and it is this padding which absorbs the moisture from the clothes being ironed, unless the padding is maintained at a temperature higher than 212° F.

As a means of maintaining the padded surface of each of the rollers 12 at a sufficiently high temperature to prevent its absorption of moisture and to thereby prevent a substantial accumulation of moisture on the padded surface, my invention contemplates the use of auxiliary heating shoes, each of which is arcuate in cross section for co-operative contact with a portion of the surface of its respective roller. In the illustrations each shoe is designated as a whole by the numeral 20. The type of heating shoe

illustrated in Figures 1 to 3 is heated electrically by means of what is known to the trade as strip heating elements 21, 22, and 23. The surfaces of these elements are suitably insulated against being shorted by contact with the damp surface of the roller. These strip elements are rigidly attached in parallel relation to a plurality of laterally aligned arms 24, 25, and 26, as shown, the opposite ends of which are rigidly connected to a bar or shaft 27. This shaft is journaled in suitable brackets 28 and 29 preferably mounted on the plates 14 and 15 respectively. Thus the shoe 20 is mounted so that it may be moved away from the roller surface in case the surface temperature exceeds a desired limit, and to prevent burning the padded surface in case it is necessary to stop the roller for any reason.

As a preferred means of automatically controlling the movement of the heating shoe 20 into or away from contact with the surface of the roller 12, we provide a suitably mounted damper motor 30. Such a motor is generally available commercially, and is described fully in Reissue Patent #18,503, granted to L. L. Cunningham on June 21, 1932. It is simply an automatic reversing back geared motor, which moves a crank arm 31 approximately one half a revolution in one direction on the first closing of the circuit, automatically breaks the circuit, and then returns the arm through the same arc on the next closing of the circuit, the arm always stopping at the same points at opposite ends of its arcuate throw. The eye of an eye bolt 32 receives the end of the crank arm 31, while the opposite end of the eye bolt is slidably held within a slightly larger perforation in an extension 33 on the arm 26. A compression spring 34 is positioned on the eyebolt 32 between the upper surface of the extension 33 and a spring tension adjusting nut 35. Thus as the motor moves the crank arm toward the position shown in Figure 1, the eyebolt and its encircling spring move the entire shoe 20 into contact or near contact with the surface of the roller. The tension adjustment of the spring 34 determines the pressure exerted against the roller surface by the shoe 20, if actual contact is desired.

On the next closing of the motor circuit the crank arm is moved thru an arc of approximately 180°, and thus aids in moving the shoe 20 away from the roller surface. To aid the motor in lifting the weight of the shoe, however, we provide an expansion spring 36, one end of which is suitably connected to the shoe and the other end of which is adjustably connected to a suitable bracket 37. The tension of this spring is adjustable by means of an adjusting nut 38. With the parts of the mangle in the relative positions shown in Figure 1, the spring 36 is expanded, and the shoe has been moved into contact or near contact with the roller surface by the motor, and against the tension of this spring 36. Naturally when the crank arm moves to the opposite end of its throw, the contraction of the spring 36 aids in lifting the shoe. As a matter of fact I prefer to use a spring sufficiently strong to assume the main portion of the burden of lifting this shoe.

The automatic closing of the motor circuit is accomplished by a fixed temperature thermostatic switch 39, which is responsive to temperature changes in a heat conducting element 40, one end of which is connected internally with the switch, and the opposite end of which is adjustably held in a position of contact or near con-

tact with the surface of the roller 12, as it rotates. This switch 39 may be made to operate the motor when the roller surface reaches a high temperature of 300° Fahrenheit, and again when it reaches a low temperature of 240° Fahrenheit. The temperature limits may, of course, be varied to suit the particular operation.

As a means of controlling the flow of current to the heating elements 21, 22 and 23, of the shoe 20, any suitable switch 41 operable by the motor 30 may be used. The switch illustrated is a simple toggle switch provided with a switch arm 42, which is bifurcated at its free end for operation by a crank arm 43. This crank arm 43 is operated by the motor 30, and its movement is coordinated with the movement of the crank arm 31, so that when the crank arm 31 is moving in a shoe lowering direction, the crank arm 43 contacts the switch arm 42, and closes the heating element circuit before the shoe actually contacts the roller surface. Similarly the heating element circuit is opened shortly after the motor begins to operate in the opposite direction.

The embodiment disclosed in Figures 5 and 6 differs mainly from the above described embodiment in that the shoe 20A, instead of being electrically heated is so constructed that it may be heated by the circulation of fluid therethrough (either gas, vapor, or liquid). This shoe, therefore, includes a plurality of hollow tubes or flues 21A, 22A, and 23A, the open opposite ends of which communicate respectively with headers 44 and 45, which in turn are in communication respectively with a source of heated fluid supply 35 and a return line by means of pipes or tubes 46 and 47. Due to the fact that the temperature of the fluid heated shoe may be much more easily controlled than that of the electrically heated shoe and may be more easily kept at a fairly constant comparatively low temperature, (approximately 280°-320° Fahrenheit) it is not absolutely necessary to provide an automatic means for moving the shoe away from the roller surface, altho the same means as above described for the electric heater may be used if desired. As an alternative, we provide a hand operated lever 48 pivotally mounted on a suitable bracket 49 at point 50, and operably connected to the shoe 20A by means of a link or bolt 51, as shown. The handle may be maintained in any desired position by means of a ratchet 52, and a handle operated pawl 53. All other parts in this embodiment are substantially identical to the parts in the embodiment first described.

In Figure 7 is illustrated an embodiment of the invention which differs from the Figures 5 and 6 embodiment only in that the shoe 20B is made of a single hollow properly shaped tube instead of a plurality of tubes. Fluid is circulated through this shoe in substantially the same manner, and automatic means for raising and lowering the shoe may or may not be employed, as desired. All other parts are substantially identical to the parts in the embodiment first described.

From the above description it will be seen that we have provided a mangle construction in which the surfaces of the ironing rollers are supplementally heated independent from the heat ordinarily provided by the respective ironing shoes.

Operation

In operation, as the roller 12 rotates, its padded surface is heated by proximity to the surface of

chest 10. As wet clothing is ironed by passing between the adjacent surfaces of these two members, the moisture in the clothing cools the padded surface of the roller 12, and when the roller surface temperature drops below approximately 240° Fahrenheit the heat conducting element 40 throws thermostatic switch 39, closing the motor circuit. The motor 30, thru crank arm 31, then moves heating shoe 20 into contact or near contact with the surface of roller 12, depending on the predetermined or adjusted length of eye-bolt 32, the motor circuit being automatically opened at the completion of this movement. During this movement of the shoe 20 toward the roller surface, the switch 41 is also thrown, closing the electrical circuit to the heating elements 21, 22 and 23. The proximity of the auxiliary shoe 20 heats the surface of the roller 12 during its rotation until it reaches the thermostatic control temperature, say 300° Fahrenheit, at which time the thermostatic switch again closes the motor circuit, the shoe 20 is moved away from the roller by the motor 30, the motor circuit is broken, and the shoe heating circuit is broken.

While we have described and illustrated only three embodiments of our invention, we are aware that numerous changes and alterations may be made in the construction of devices embodying our invention without departing from the combination of parts disclosed, and we do not wish to be limited except by the prior art and by the scope of the appended claims.

We claim:

1. A mangle or ironer comprising: a heated ironing shoe; an ironing roller mounted to co-operate with said shoe; an auxiliary heating shoe mounted for movement toward and away from the peripheral surface of said roller; means for heating said auxiliary shoe; and thermostatically controlled power means for moving said auxiliary shoe toward and away from the peripheral surface of said roller, said power means being responsive to temperature changes on the peripheral ironing surface of the roller.

2. A mangle or ironer comprising: a heated ironing shoe; an ironing roller mounted to co-operate with said shoe; an auxiliary heating shoe mounted for movement toward and away from the peripheral surface of said roller; means for heating said auxiliary shoe; thermostatically controlled means for moving said auxiliary shoe toward and away from the peripheral surface of said roller; and means operated by said thermostatically controlled means for controlling the means for heating said auxiliary shoe.

3. An ironer or mangle comprising: an ironing roller; a co-operating heated ironing shoe; an auxiliary heated shoe adjustably mounted for independently contacting and heating a portion of the peripheral surface of said roller as it rotates; electric heating elements for heating said auxiliary shoe; and a thermostatically controlled motor responsive to changes in the temperature of the roller surface for moving said auxiliary shoe toward and away from the peripheral surface of said roller.

4. An ironer or mangle comprising: an ironing roller; a co-operating heated ironing shoe; an auxiliary heated shoe adjustably mounted for independently contacting and heating a portion of the peripheral surface of said roller as it rotates; means affording circulation of heated fluid thru said auxiliary shoe; and a thermostatically controlled motor responsive to the temperature of the roller surface for adjusting the

position of said auxiliary shoe with relation to the adjacent peripheral surface of said roller.

5. A mangle comprising: an ironing roller; an ironing shoe co-operatively engaging a portion of the surface of said roller; means for heating said ironing shoe; an auxiliary heating shoe adjustably mounted in proximity to the peripheral surface of said roller for heating said surface; means for heating said auxiliary shoe; means for shifting said auxiliary shoe relative to said roller and thermostatically controlled means responsive to temperature changes of the peripheral surface of said roller for controlling the temperature and relative position of said auxiliary shoe.

6. A mangle or ironer comprising: a heated ironing shoe; an ironing roller mounted for co-operation with said shoe; an auxiliary heating shoe mounted for movement toward and away from the peripheral surface of said roller; means for heating said auxiliary shoe; thermostatic means responsive to changes in the load placed on the roller during its operation and a prime mover responsive to said last named means for moving said auxiliary shoe toward and away from the peripheral surface of the roller to thus maintain the roller surface at a temperature above a predetermined temperature.

7. A mangle or ironer comprising: a heated ironing shoe; an ironing roller mounted for co-operation with said shoe; an auxiliary heating shoe mounted for movement toward and away from the peripheral surface of said roller; means for heating said auxiliary shoe; power means for moving said auxiliary shoe toward and away from the peripheral surface of said roller; and means responsive to changes in the heat load placed on said roller during its operation for controlling the operation of said power means.

8. A mangle or ironer comprising: a heated ironing shoe; an ironing roller mounted for co-operation with said shoe; an auxiliary heating shoe mounted for movement toward and away from the peripheral surface of said roller; means for heating said auxiliary shoe; power means for moving said auxiliary shoe toward and away from the peripheral surface of said roller; and thermostatic means for controlling the operation of said power means, said means being responsive to predetermined temperature limits on the peripheral ironing surface of said roller.

9. A mangle or ironer comprising: a heated ironing shoe; an ironing roller; an auxiliary roller heating shoe mounted for movement toward and away from the peripheral surface of said roller; means for heating said shoe; and a thermostatically controlled motor responsive to changes in the heat load placed on said roller during its operation for moving said auxiliary shoe toward and away from the peripheral surface of said roller.

10. In a heating and drying device, a roller rotatable on its axis, a primary heating surface in close proximity to a portion of the roller periphery and between which surface and roller periphery the material to be heated and dried is passed, an auxiliary heating device for applying heat externally to another portion of the roller periphery to heat the roller independently of the primary heating surface and without the interposition of the material being heated and dried between the roller periphery and the auxiliary heating device, and heat sensitive means for controlling the application of heat to the roller by the auxiliary heating device in response

to the temperature of the roller periphery, said heat sensitive means maintaining the roller at a temperature sufficiently high to substantially prevent the accumulation of moisture on the roller irrespective of the varying heat load imposed by the particular material being passed between the roller and the primary heating surface.

11. In a heating and drying device, a roller rotatable on its axis and having a moisture absorbent periphery, a primary heating surface in close proximity to a portion of the roller periphery and between which surface and roller periphery the material to be heated and dried is passed, an auxiliary heating device for applying heat externally to another portion of the roller periphery to heat the same independently of the primary heating surface and without the interposition of the material being heated and dried between the roller periphery and the auxiliary heating device, and means including the auxiliary heating device for maintaining the roller periphery at a temperature sufficiently high to substantially prevent the accumulation of moisture on the roller periphery irrespective of the heat load imposed by the particular material being passed between the roller periphery and the primary heating surface.

12. In an ironing device, an ironing roller having a moisture absorbent covering which is rapidly deteriorated when its temperature exceeds a given value, a primary heating surface in close proximity to a portion of the roller periphery and between which surface and the roller periphery the material to be ironed is passed, an auxiliary heating device adapted to supply heat to another portion of the roller periphery, and thermostatic means responsive to the temperature of the roller periphery for preventing the auxiliary heating device from raising

the temperature of the roller covering beyond said value which causes rapid deterioration of the covering, said thermostatic means, however, maintaining the roller at a temperature sufficiently high to substantially prevent the accumulation of moisture on the roller irrespective of the varying heat load imposed by the particular material being passed between the roller and the primary heating surface.

13. The method of heating and drying sheet material which consists in passing the material between a primary heating surface and a roller having a moisture absorbent surface and applying sufficient supplemental heat externally to the roller at another point of its periphery without the interposition of the material between the supplemental heating means and the roller to maintain the periphery of the roller at a temperature sufficiently high to substantially prevent the accumulation of moisture on the surface of the roller irrespective of the heat load imposed by the particular material being passed between the roller and the primary heating surface.

14. The method of heating and drying sheet material which consists in passing the material between a primary heating surface and a roller having a moisture absorbent surface and applying sufficient supplemental heat to the roller at another point of its periphery without the interposition of the material between the supplemental heating means and the roller to maintain the periphery of the roller at a temperature sufficiently high to substantially prevent the absorption of moisture by the surface of the roller irrespective of the heat load imposed by the particular material being passed between the roller and the primary heating surface.
